UNITED STATES PATENT OFFICE.

SAMUEL ERB AND WILLIAM ERNEST MORELL, OF CHEMAINUS, CANADA.

FIRE-EXTINGUISHER.

SPECIFICATION forming part of Letters Patent No. 766,232, dated August 2, 1904.

Application filed April 7, 1904. Serial No. 201,958. (No model.)

To all whom it may concern:

Be it known that we, SAMUEL ERB, a citizen of the United States of America, and WILLIAM ERNEST MORELL, a citizen of the Dominion of Canada, both residents of the town of Chemainus, district of Cowichan and Province of British Columbia, Canada, have invented certain new and useful Improvements in Fire-Extinguishers, of which the following is a specification.

This invention relates to safety fire devices, and has for its objects, first, to indicate the temperature of a room; second, to regulate said temperature; third, to sound a warning when the temperature varies beyond certain definite limits; fourth, to sound a local alarm when the heat approaches a dangerous limit; fifth, to turn on live steam into said room if the temperature exceeds said dangerous limit; sixth, to turn off the ventilating-flues, so as to smother the fire; seventh, to turn on a stream of water if the temperature continues to rise; and eighth, to sound a general alarm. We attain these objects by the devices and mechanism illustrated in the accompanying drawings, in which—

Figure 1 is a vertical longitudinal section of a kiln equipped with our apparatus. Fig. 2 is a horizontal section thereof, said section being taken on a plane just above the expansion-pipe. Fig. 3 is an enlarged detail of the operating portion of the apparatus. Fig. 4 is an enlarged section of the end of the weight-shelf, and Fig. 5 is a plan of the water-sprinkling pipes.

Similar numerals of reference refer to similar parts throughout the several views.

We have illustrated our invention as applied to a kiln 1, heated by means of steam-pipes 2, 40 placed in any convenient position therein. To the roof of said kiln 1 is suspended the metal rod or pipe 3, preferably made of brass. The inner end of this pipe 3 is supported by the hanger 4 and is rigidly held from moving 45 therein by the nuts 5 on the pipe 3 and engaging the hanger 4. The other supports for the pipe 3 are simply loops 6, adapted to support its weight, but to allow it to move longitudinally with perfect freedom. The pipe 3 is

made in sections of any convenient length, and 50 the sections are joined together by the fusible couplings 7, made of such metal as will melt when the temperature rises to a certain dangerous point. The pipe 3 passes through the end wall of the kiln 1, and to this end are secured the various devices whereby the objects 55 of our invention are attained. To the outside of this wall is secured, directly below the pipe 3, the horizontal shelf 8, extending at right angles to the pipe 3 and adapted to support 60 various weights in the manner described below. Extending out from the wall at the same level as the shelf 8 and to one side of the pipe 3 is the arm 9, carrying at its extremity the pulley 10 in line with the pipe 3. 65

The pipe 3 extends out from the wall and has a hook 11 secured to its end adapted to engage the wire cable 12, passing over the pulley 10 and supporting the weight 13 at 70 its end in such a manner that the weight will always be pulling the pipe 3 toward the pulley 10. As the temperature in the kiln varies the pipe 3 will vary in length, lifting the weight 13 if it cools and lowering it if it becomes warmer. The length of the pipe de- 75 pends directly on the temperature of the kiln, and therefore by attaching a pointer 14 to the pipe 3 and a temperature-scale 15 to the arm 9 and by adjusting the pointer on the pipe to point to the proper temperature on said scale 80 the temperature of the kiln will be indicated at any time.

We have shown the kiln 1 as heated by means of the steam-pipes 2, the steam coming from the main pipe 16 and entering the kiln 85 through the central pipe 17, having the gate-valve 18 therein. A lug 19 is adjustably secured to the pipe 3 and is adapted to engage the bell-crank 20, pivoted to the arm 9. The bell-crank has its upper arm formed into a 90 Y shape, and the lug 19 engages loosely between the prongs thereof. The other end of the bell-crank is connected by means of the link 21, having a turnbuckle 22 therein, with the lever 23 of the gate-valve 18. In this way 95 the temperature of the kiln is automatically controlled, the movements of the pipe 3 acting through the bell-crank 20, the link 21,

and the lever 23 to control the opening of the gate-valve 18, and therefore the temperature of the kiln.

Should the temperature rise or fall beyond certain fixed limits, we have devised the following warning-signals: To the pipe 3 are adjustably secured the lugs 24 and 25. Secured to the arm 9 at points between the lugs 24 and 25 and adapted to be engaged by them are the spring contact-pieces 26 and 27, and between these are the contact-buttons 28 and 29, Figs. 1 and 3. Electric wire 30 leads from the buttons 28 and 29 to the battery represented at 31, which may be located at any convenient place, and to the electric bells 32 and 33, preferably made to sound in different tones. The spring contact-piece 26 is connected to the bell 32 by the wire 34 and the spring contact-piece 27 to the bell 33 by the wire 35. If the temperature increases too high, the pipe expands, so that the lug 24 presses the spring 26 against the button 28, forming a complete electric circuit by the wires 30 and 34 through the bell 32, which therefore rings a warning that the temperature has risen too high. Similarly when the temperature falls too low the lug 25 presses the spring 27 against the button 29, forming a circuit by the wires 30 and 35 through the bell 33, which therefore rings a warning that the temperature has fallen too low. The springs 26 and 27 bend freely, so as not to interfere with the movement of the lugs 24 and 25. The bells 32 and 33 may be set up in any desired place and may be duplicated in sets in several places—such as in the office-building, the boiler-room, or the engine-room—and are readily distinguishable on account of their different tones.

The cross-head 36 is secured to the pipe 3 by means of the nuts on each side of it and rests on the shelf 8 and slides thereon when the pipe 3 expands or contracts. In this cross-head 36 are screwed the set-screws 37 at various intervals therein and adapted to engage and to push off the shelf the hereinafter described weighted bars. The length of these set-screws protruding beyond the cross-head 36 can be regulated simply by screwing them in or out in the cross-head.

A series of notches 38 are made in the outside of the shelf 8, said notches having sides 39 whose upper edges are inclined, as shown in Fig. 4. In these notches 28 hang the weighted bars 40 on the roller-arms 41, engaging and supported by the inclined upper edges of the sides 39. The bars 40 extend upward above the shelf 8 and support below said shelf the weights 42. These weights are adjustable by the usual unit method of adding or removing one or more parts thereof. The weighted bars 40 are connected by means of wire cables to the various valves which it is desired for them to operate. For instance, the cable 43 connects a weight 42 with the

valve 44 of the local danger-whistle. The cable 45 connects another weight 42 with the valve 46, controlling the live-steam pipe, whereby when its valve is opened the kiln is flooded with live steam, and thus the fire is smothered. The cable 47 connects another weight 42 with the damper 48 in the ventilator-stack, preventing a draft in the kiln and aiding in smothering the fire. The cable 49 connects another weight 42 with the valve 50, controlling the water-sprinkling pipes, and the cable 51 connects another weight 42 with the valve 52 of the main whistle of the plant.

Each of the weighted bars 40 is opposite to one of the set-screws 37 in the cross-head 36, secured to and moving with the pipe 3. It is evident then that the action of each of the weights 42 is independent of all the others, inasmuch as by adjusting any one of the screws 37 out farther than the other screws 37 the corresponding weighted bar 40 will be pushed on its roller-arms 41 up the inclined edge 39 and allowed to drop from the shelf 8 before any of the other weights, and therefore to act on its particular apparatus before the others act. This, however, is only in case of a gradual increase in the temperature of the kiln, for if the temperature rises quickly and becomes sufficiently high to melt one of the fusible couplings 7 before the pipe 3 has expanded enough to push off any of the weights or to ring the electric alarm then the weight 13 pulls the loosened part of the pipe suddenly forward, and thus pushes off all the weights 42 at practically the same time.

In equipping a kiln with our apparatus we prefer to construct the water-sprinkling system as shown in Figs. 1 and 5, the water-pipe 53, leading from the valve 50 into the upper part of the kiln and connecting directly to the head-pipe 54, which in turn connects with the series of pipes 55, leading out of said pipe 54 and being connected together at intervals by the supplementary head-pipes 56, running parallel with the pipe 54. All these pipes we prefer to perforate with holes set at an angle about forty-five degrees to the vertical, so that the small streams of water issuing from one pipe will intersect similar streams from the adjacent parallel pipe.

It is evident that in the arrangement of the details it is necessary to allow a wide latitude of variation, especially in the location and arrangement of the various pipes and valves, and therefore in the connections between the weights and the valves.

Having now described our invention, what we claim, and desire to secure by Letters Patent, is—

1. In a fire-protective apparatus, the combination with a fixed hanger, of an expansion-pipe secured thereto and extending therefrom, a cross-head secured near the end of said expansion-pipe and having adjustable screws therethrough, and means engaged by said

screws whereby fire-alarm and fire-extinguishing apparatus is brought into action.

2. In a fire-protective apparatus, the combination with a fixed hanger, of an expansion-
5 pipe secured thereto and extending therefrom said pipe being divided in sections joined by metal couplings having a low fusing-point, means secured to the free end of said expansion-pipe whereby it is always kept in ten-
10 sion, and a cross-head secured to said expansion-pipe and adapted to engage and actuate fire-alarm and fire-protective apparatus.

3. In a fire-protective apparatus, the combination with a fixed hanger, of an expansion-
15 pipe secured thereto and extending therefrom, an adjustable lug secured to the free end of said expansion-pipe, a pair of spring contact-pieces adapted to be engaged and bent by said lug, a corresponding pair of stationary
20 contact-pieces one adapted to be touched by its spring contact-piece when said pipe expands beyond a certain point and the other adapted to be touched by its spring contact-piece when said pipe contracts below a certain
25 point, and a pair of electric circuits comprising a common source of electric energy a pair of electric bells and connecting-wires whereby either one of said bells may be rung when said lug presses the spring contact-piece against
30 the corresponding stationary contact-piece.

4. In a fire-protective apparatus, the combination with a fixed hanger, of an expansion-

pipe secured thereto and extending therefrom said pipe being divided in sections joined by metal couplings having a low fusing-point, a 35 flexible cable secured to the end of said pipe and passing over a pulley and supporting a weight whereby said pipe is always kept in tension, a cross-head secured near the end of said expansion-pipe and adapted to engage 40 and actuate fire-alarm and fire-extinguishing apparatus.

5. In a fire-protective apparatus, the combination with a fixed hanger, of an expansion-
45 pipe secured thereto and extending therefrom said pipe being divided in sections joined by metal couplings with a low fusing-point, a flexible cable secured to the end of said pipe and passing over a pulley and supporting a weight whereby said pipe is always kept in 50 tension, a cross-head secured to said expansion-pipe, a series of weighted bars supported near said cross-head and adapted to be pushed thereby from off their supports and to actuate fire-alarm and fire-extinguishing apparatus when one of said fusible couplings melts. 55

Signed at Chemainus this 25th day of March, 1904.
